PUNCHING AND MARKING MACHINE

Axel A. Lawson, Beverly, Mass., assignor to
United Shoe Machinery Corporation, Paterson,
N. J., a corporation of New Jersey

Application April 16, 1934, Serial No. 720,701

2 Claims. (Cl. 12—17)

This invention relates to machines for operating upon shoe part blanks and is herein illustrated as embodied in a machine for punching and marking soles.

5 In the manufacture of shoes the soles of which are secured to the upper by adhesive it is common practice in locating the sole relatively to the upper to place along the marginal portions of the sole a coating of adhesive to form part of the
10 means for securing the sole to the upper. This coating of adhesive ordinarily should not extend rearwardly by an appreciable distance beyond the breast line of the sole in order that it will not interfere with the positioning of the shoe
15 relatively to gage devices in the heel-seat fitting operation which is performed subsequently to the sole-attaching operation. It is therefore customary to mark upon the sole the approximate location of the breast line prior to the application of
20 the adhesive in order to determine the limits beyond which the adhesive should not be applied.
In view of the foregoing, it is an object of the invention to provide improved mechanism for placing upon a sole marks in predetermined position
25 relatively to an end thereof to indicate the breast line of the sole. Preferably and as illustrated, this mechanism comprises a work support, a gage for positioning a sole upon the support and a marking device mounted for reciprocation relatively to the support, together with means for locating the marking device along the support in position to mark the sole at the breast line thereof.

30 In attaching the sole to the upper by means of one type of machine which is extensively employed use is commonly made of a mechanism comprising a member adapted to enter a gage hole in the heel portion of the sole in locating the sole relatively to the upper prior to forcing the sole against the upper under pressure. The gage hole referred to is preferably located along a median line of the heel portion of the sole and is usually punched in the sole at a point near the center of the heel-seat portion. Since the
35 operation of punching the sole and the marking operation above referred to are both performed prior to the attachment of the sole to the upper I propose to combine the two operations, thus to reduce the number of separate operations required. To this end the marking device and a punch are preferably mounted upon a member arranged for reciprocation relatively to the work support so that the punching and marking operations upon a sole can be performed simultaneously.

Other objects and features of the invention will be apparent from the following detailed description when taken in connection with the accompanying drawings and will be pointed out in the claims.

5

In the drawings:—

Fig. 1 is a perspective view of a machine constructed in accordance with one embodiment of my invention;

Fig. 2 is a side elevation partly in section of the 10 machine;

Fig. 3 is a perspective view of a sole showing a punched hole and breast marks resulting from an operation of the machine;

Fig. 4 is an exploded view illustrating the 15 punching and marking device;

Fig. 5 is a perspective view of the marker;

Fig. 6 is a perspective view showing mechanism for adjusting the position of the marker;

Fig. 7 is a perspective view illustrating a modified form of a punching and marking machine in which the sole is gaged from the forepart; and

Fig. 8 is a view partly in section illustrating an alternative form of mechanism for adjusting the marker. The machine illustrated in Figs. 1 and 2 is particularly adapted for use in punching and marking sole blanks such as blank 10 (Fig. 3) to produce therein a gage hole 12 in the heel portion of the blank and marks or indentations 14 at predetermined distances from the heel-end portion 30 of the blank to indicate the approximate breast line of the sole beyond which the marginal coating of adhesive 15 should not extend in a rearward direction.

The machine comprises a C-shaped frame 16 having an extension 18 in which is mounted a plunger 20 carrying a punch 22 and a marking device 24 arranged to be reciprocated relatively to a work support 26 by means of a shaft 28 and pin 30. The punch 22 which is positioned in a bore 32 in the plunger 20 is arranged to cooperate with a female die member 36 mounted in an opening 38 in the work support 26.

For locating a sole, such as sole 10, relatively to the punch there is provided gage mechanism comprising a plate 40 adapted to be engaged by the heel portion of the sole. The gage plate 40 is mounted for sliding movement along the upper surface of the support 26 and can be adjusted laterally of the punch by means of a knob 42 slidably mounted upon a pin 44 carried by the plate and normally forced toward the plate 40 by a spring 46. The pin 44 extends upwardly through a slot 48 in a fixed plate 50 which overlies the plate 40, and the knob 42 can be selectively 55

located in any one of several positions in the slot for locating the gage plate 40 in position to engage the heel end of a sole at selected predetermined distances from the center line of the 5 punch, thus to insure that the gage hole is punched approximately at the middle of the heel seat in soles of different sizes, or for shoes of different styles. The plate 50 has an extension 52 which overlies the die member 36 and has an 10 opening 54 therein to permit the punch to operate upon a sole which has been brought into engagement with the gage plate 40. The plate 50 thus acts as a stripper plate to prevent the sole from rising from the work support as the punch 15 is withdrawn.

The work support 26 is provided with a nose 56 which extends beyond the forward portion of the support and is beveled as indicated by reference character 58 to provide clearance for the 20 heel breast leaf 60 of the sole, which is bent toward the forepart of the sole out of the line of operation of the punch. The construction referred to makes it possible to locate the sole flat upon the work support in position to be operated 25 upon by the punch and marking device 24.

Means is provided for locating sole blanks in such manner that the median line of the heel-end portion thereof is positioned along the work support 26 and intersects the center line of the punch 30 22. As shown, this is accomplished by means of two pairs of gages 62 and 64 (Fig. 1). The gages 62 comprise arms 66 which are adapted to engage a blank along a heel-end portion thereof rearwardly of the punch 22. These arms are 35 pivotally mounted at 68 upon the work support 26 and have integral therewith interengaging arms 70 so arranged that the gages 62 will be caused to move by equal distances inwardly or outwardly of the center line of the work support. 40 The gages 62 are normally forced inwardly by a spring-pressed plunger 72 (Fig. 2) which engages a portion of one of the arms 70. The gages 64 constitute forepart gages and comprise arms 74 which are pivoted at 76 upon a bracket 78 secured to the frame 16 and have interengaging 45 arm portions 80 likewise adapted to cause equal movement of the gages 64 inwardly or outwardly of the center line of the work support 26. The gages 64 are normally forced inwardly by means 50 of a spring 82, inward movement being limited by a set screw 84 which engages one of the arm portions 80. The gage mechanism just described makes it possible readily to locate a sole upon the work support 26 with the center line of the heel 55 portion of the sole located for operative position by the punch, it being necessary only to force the sole inwardly between the gages 64 and the gages 62 until the heel-end portion of the sole contacts with the gage plate 40. 60 The marking device 24, as shown in Figs. 2 and 4, comprises a shank 86 which is secured to the plunger 20 by screws 88 which extend through openings 90 in the marking device into openings 92 in the end portion of the plunger 20, there 65 being a groove 94 in the plunger adapted to receive portions of a projection 96 on the shank 86 of the marking device for holding the parts in rigid position. The shank 86 is provided with a bore 98 having positioned therein a plunger 100 70 which carries a bracket 102 constituting a support for a marker 104. Surrounding the plunger 100 is a spring 106 which tends normally to force the bracket and marker downwardly yieldingly to apply pressure to the marker upon descent of 75 the plunger 20, thus providing for the operation

of the marker upon soles of different thicknesses. The bracket 102 has ways 108 adapted to support the marker 104 which has projecting portions 110 (Fig. 5) slidably engaging the ways, whereby the marker may be moved in a direction parallel to the center line of the work support 26. The marker itself is provided with two spaced knife edges 112 which extend transversely of the work support and which are suitable for producing marks or indentations such as indentations 14 in a blank 10 (Fig. 3). Extending laterally from the knife edges is a projection 114 which is slidable along the under surface of one of the ways 108. This projection is provided with a beveled portion 116 which serves as a pointer 15 to indicate the position of the marker along a scale 118 (Fig. 1) carried upon one side of the bracket 102.

The marker 104 is arranged for movement manually along the ways 108 by means of a screw 20 120 (Figs. 1, 4 and 6) positioned in the bracket 102 and having two shoulders 122 between which is positioned one arm 124 of a bell crank lever 126 mounted upon a pivot 128 in the bracket. The bell crank lever has an end portion 130 located in 25 a slot 132 in the side of the marker 104 opposed to the pointer 116. Upon rotation of the screw 120 the bell crank lever is moved angularly thereto to adjust the position of the marker along the ways 108. To hold the marker in fixed position there 30 is provided a set screw 134 adapted to prevent rotation of the screw 120. The scale 118 is marked arbitrarily with divisions so that after the setting of the marker has once been determined for a sole of given size, the marker subsequently can be readily positioned for operation upon soles of that size. Thus it will be seen that the marker can be located at predetermined distances, dependent upon the size of soles being operated upon, from the gage 40 thereby to determine the location of the marks relative to the heel end of the sole. The mechanism just described thus provides comparatively simple adjustment for the marker for different sizes of 35 soles.

In order to prevent the operator from placing his fingers in alignment with the work-supporting and marking devices upon insertion of a blank in the machine there is provided a safety plate 136 (Fig. 1) which is spaced from the frame 50 50 extension 18 by collars 138 and secured in a rigid position to the extension by screws 140 extending through the collars. The lower end portion of the plate extends downwardly to within a short 55 distance of the work support 26.

In the operation of the machine, the marker 104 is positioned along the scale 118 at a predetermined point corresponding to the size of the sole to be operated upon. The sole is then placed upon the work support 26 forcing it between the 60 gages 62 and 64 until the heel end contacts the gage plate 40 thus to locate the sole longitudinally and laterally of the punch 22 and marker 104. Upon operation of the plunger 20 the 65 punch will produce a gage hole approximately in the center of the heel seat, and the marker will produce indentations in the sole located approximately at the breast line.

Figs. 7 and 8 illustrate a modified form of 70 punching and marking machine provided with a gage mechanism for locating soles so that the gage hole and indentations will be made at predetermined distances from the toe end of the sole. The illustrated machine adapted for this purpose 75 comprises a frame 142, a work support 144, a

plunger 146, punch 147, a stripper plate 148, fore-part gages 150, heel end gages 152, and a marker 154, similar in construction to corresponding parts of the machine illustrated in Figs. 1 and 2.

- 5 In this instance the marker 154 is mounted in ways 156 carried by the lower end of a plunger 158 and is arranged for longitudinal adjustment by means of a screw 160, which makes threaded engagement with the marker and is operated by 10 a knurled nut 162, longitudinal movement of the screw itself being prevented by a shoulder 164 thereon, and the nut itself which engage opposite sides of a plate 166 secured to the lower end of the plunger 158. The marker 154 has a pointer 15 168 which is slideable along a scale 170 upon the side of the lower end of the plunger 158. The scale 170 may be marked with three divisions which correspond to the different styles of shoes to which soles are to be attached. The scale 20 provides for the adjustment of the marker to accommodate for a variation in the distance of the breast line due to the particular heel used upon the shoe. For example, it is desired to mark the breast line on a sole to be used with a 25 Louis heel much further forwardly than for a Cuban heel. This adjustment of the marker can be readily accomplished by means of the nut 162.

In order to position soles so that the breast line will be indicated at the correct points regardless 30 of the size of the sole, there is provided a gage in the form of a plate 172 adapted to be located at predetermined distances corresponding to different sizes of soles from the center line of the punch 147 and the marker 154 in one of its adjusted positions. The gage 172 has integral therewith a split collar 174 which is slideable along a rod 176 supported by ears 178 and 180 extending from one side of the work support 144. The collar 174 is provided with a clamping screw 40 182 for securing the plate 172 in adjusted position along the rod 176. The collar 174 also carries a pointer 184 for use in setting the gage plate in predetermined position along a scale 186 marked upon the rod 176. Each scale division corresponds to the distance which the breastline moves forwardly in advancing from one size of sole to the next larger size plus a correction necessitated by the increase in length of the sole 45 between the two sizes. The collar 178 carries a clamping screw 188 by which the gage rod can be clamped in position with the scale 186 properly

located relatively to the center line of the punch. The position of the rod can readily be ascertained by placing upon the work support 144 a sole upon which the breast line is marked, positioning the sole with the marker in alinement with the breast mark, setting the gage plate 172 with the pointer 184 on the division of the scale 186 which corresponds to the size of the sole, then sliding the rod rearwardly until the gage plate 172 engages the end of the sole. The rod may then be clamped 10 into position by the screw 188 and the scale 186 will be properly set for all sizes of soles. The machine is provided with a safety plate 190 corresponding to the plate 136 of Fig. 1 but having a slot 192 in the lower part thereof through which 15 the nut 162 extends.

In the operation of the machine, after adjusting the marker 154 along a scale 170 in accordance with the style of shoe and after setting the gage plate 172 to correspond to the size of sole to 20 be operated upon, the sole is placed upon the work support 144 between the gage arms 150 and 152 and is then brought forwardly until the end of the sole engages the gage plate 172. The plunger 146 is then operated to cause downward 25 movement of the punch and marker to punch a gage hole and produce breast mark indentations in the sole which will be in predetermined position upon the forward end of the sole.

Having described my invention, what I claim 30 as new and desire to secure by Letters Patent of the United States is:

1. A machine for operating upon soles comprising a work support, a member mounted for reciprocation relative to the support, a spring-pressed plunger carried by said member and having at its lower end a plurality of ways, a marking device mounted for movement in the ways, a scale upon one of the ways, and a pointer on the marking device for indicating the position there- 35 of along the scale.

2. A machine for operating upon soles comprising a work support, a member mounted for reciprocation relatively to the support, a spring-pressed plunger carried by said member and having a plurality of ways at one end thereof, a marker mounted for sliding movement in the ways, and means for adjusting the position of the marker in the ways. 45
